INVENTOR
Henry Walter,

BY Victor J. Evans

ATTORNEY

UNITED STATES PATENT OFFICE.

HENRY WALTER, OF SANDERS, IDAHO.

CASTER.

Specification of Letters Patent.

Patented June 4, 1918.

1,268,651.

Application filed December 2, 1916. Serial No. 134,638.

To all whom it may concern:

Be it known that I, HENRY WALTER, a citizen of the United States, residing at Sanders, in the county of Benewah and State of Idaho, have invented new and useful Improvements in Casters, of which the following is a specification.

The present invention contemplates the production of a stove leg so designed to permit of a caster being connected therewith in such a manner as to enable the caster to be moved downwardly in the operation of moving the stove from one place to another, and also when the stove is at rest on the floor the caster will ascend within the base of the leg.

A further object of the invention resides in the provision of a stove leg provided with means for operating the caster of such type as to prevent any frictional contact between the caster plate and said means during the manipulation of the latter.

Furthermore, I contemplate the production of a stove leg provided with a groove in which the handle of the operating means for the casters snugly fits upon the resting action of the leg upon the floor.

With the above and other objects in view, the invention consists in the novel features, details of construction and combination of parts which will hereinafter be more fully set forth, illustrated in the accompanying drawing and pointed out in the appended claim.

Figure 1 is a front elevation of the stove leg showing the lever illustrating the lever in active position;

Fig. 2 is a bottom plan view of the stove leg showing the caster plate removed therefrom;

Fig. 3 is a section taken through line 3—3 of Fig. 1;

Fig. 4 is a top plan view of the leg showing the operating lever removed therefrom;

Fig. 5 is a perspective view of the operating lever; and

Fig. 6 is a perspective view of the caster plate.

Referring more particularly to the accompanying drawing, in which like characters of reference refer to corresponding parts in the several views, 5 denotes the stove leg provided with a hollow base 6. Formed in the central portion of the front face of the stove leg is a vertical channel 7 opening out at its lower end into the longi-

tudinal slot 8 formed in the top wall of the base 6 of the leg. Provided integral with the inner wall of the hollow base 6 is a series of spaced laterally extending lugs 9 presenting horizontal shoulders 10. The caster plate 11 to which the caster 12 is connected, is provided with a plurality of spaced concentrically arranged slots 13, adapting the caster plate to be inserted within the base and by partial rotation of the plate, will bring the slotted portions thereof to repose upon the shoulders 10 of the lugs, thus detachably connecting the caster plate with said base, as is obvious from the drawing. I have produced a novel type of substantially L-shaped lever 14 for effecting a downward vertical movement of the caster plate within the housing when it is desired to move the stove from one place to another. To this end, the horizontal head 15 of the lever is pivotally supported on the pin 16 traversing the slot 8 of the base for operatively connecting the head of the lever in the slot of said base for a vertical swinging movement. The vertical arm 17 of said lever is of substantially T-form in cross section providing at opposite sides of the stem 18 of said lever opposite laterally extending flanges 19, thus it will be seen when it is desired that the caster plate ascend within the housing, the stem of the lever will snugly engage within the channel 7 of the leg, bringing the flanges 19 of said lever in abutting engagement with the outer front face of the stove leg. As better shown in Fig. 3, the stem 18 is curved throughout its length to conform with the configuration or contour of the leg, consequently, when the stem 18 is projected into the channel 7, it accommodates the stem 18 in being snugly seated therein for the full extent of the channel and presents a neat appearance of the lever when the same is in active position. Moreover, by the provision of the flanges 19 abutting with the front face of the stove leg 5 to opposite sides of the channel 7, serves to limit the swinging movement of the lever to a caster engaging position. The character 20 denotes a loop formed on the exterior portion of the arm 17 for conveniently raising or lowering the lever, as the occasion may so demand. The extreme forward end of the head 15 of said lever is of substantially cam-shape and formed with spaced ears 21 between which is revolvably mounted a roller 22, conse-

quently when the lever is swung in a downward vertical direction, it will bring the roller 22 into contact with the outer face of the caster plate and thus prevent any frictional contact of the lever with said plate, during the manipulation of the lever in either a raised or lowered position.

From the foregoing description, taken in connection with the accompanying drawing, 10 the advantages of construction and the method of operation will be readily apparent to those skilled in the art to which the invention relates, and while I have described the principles of operation of the 15 invention, together with the device which I now consider to be the best embodiment thereof, I desire to have it understood that the device shown is merely illustrative, and that such changes may be made when desired as are within the scope of the claim 20 appended hereto.

What is claimed as new, is:

In combination with a stove leg provided

in the front face thereof with a vertically extending channel, and a hollow base provided on and beyond the lower end of the leg having a slot communicating with the channel, a caster plate movably supported in said base, an operating lever of T-form in cross section having a reduced shank and 25 pivotally supported in the slot of the base for causing a downward vertical movement of the caster-plate, the reduced shank of the operating lever being curved throughout its length to conform with the contour of 30 the leg and adapted to rest in the vertically extending channel with the head thereof contacting with the front face of the leg at points to opposite sides of said channel 35 when the lever is in caster engaging position, and a roller rotatably mounted in the lower end of the operating lever, substantially as and for the purpose specified. 40

In testimony whereof I affix my signature.

HENRY WALTER.
